DESIGN FOR A SHOE

Leo J. Jordan, St. Louis, Mo., assignor to International Shoe Company, St. Louis, Mo., a corporation of Delaware

Application August 5, 1935, Serial No. 57,956

Term of patent 14 years

To all whom it may concern:

Be it known that I, Leo J. Jordan, a citizen of the United States, residing at 4547A Durant Street, St. Louis, Missouri, have invented a new, original, and ornamental Design for a Shoe, of which the following is a specification, reference being had to the accompanying drawing, forming a part thereof, in which

Figure 1 is a view of the left side of the shoe.

Figure 2 is a drawing of the right side of the shoe.

Attention is directed to the appliquéd forming the upper front portion of the shoe. This is colored to effect a desirable color scheme in combination with the rest of the shoe.

I claim:

The ornamental design for a shoe, substantially as shown and described.

LEO J. JORDAN.
